UNITED STATES PATENT OFFICE.

THOMAS F. ROWLAND, OF NEW YORK, N. Y.

VALVE.

SPECIFICATION forming part of Letters Patent No. 235,383, dated December 14, 1880.

Application filed August 2, 1880. (No model.)

To all whom it may concern:

Be it known that I, THOMAS F. ROWLAND, of the city, county, and State of New York, have invented a new and useful Improvement 5 in Valves, of which the following is a full, true, and exact description, reference being had to the accompanying drawings.

The object of my invention is to make a valve which can be very quickly opened, can 10 be made absolutely tight, and at the same time, when opened, will leave the passage entirely unobstructed.

My invention is particularly applicable to 15 valves for preventing the passage of gas. The valve itself is a double valve closing against two seats, thereby insuring greater certainty and tightness. When opened the entire valve mechanism is withdrawn from the passage, leaving said passage entirely clear. My valve, 20 however, is not slid out in the manner of a slide-valve, but is in the first place withdrawn from its seat laterally, and is then elevated and withdrawn entirely from the passage. In seating the double valve a wedge movement 25 is employed in order to cause it to rest firmly against its seats. The withdrawing motion is occasioned by a double-screw mechanism, which greatly multiplies the longitudinal movement of the valve-stem.

My invention will be clearly understood from 30 the accompanying drawings, in which similar letters refer to similar parts.

Figure 1 represents a perspective view across 35 the valve-chest, the outer casing being partly broken away to show the valve-operating mechanism. Fig. 2 represents a section at right angles to Fig. 1, showing the valve closed; Fig. 3, a similar section showing the valve open.

The valve casing or chest is represented 40 generally at B, showing suitable connections for the gas-pipes, and it is provided with an upper chamber, V, (shown fully in all the drawings,) into which the valves A are withdrawn when opened. These valves are round 45 plates A A, seating at S S S S, as shown in Fig. 2, and they are withdrawn into the upper chamber, V.

The stem, which does not itself rotate, is elevated by a hand-wheel, D, which wheel is 50 provided with a low-pitch screw, F, screwing into the support E. This hand-wheel D re-

volves a tube provided with an inner screw-thread, which engages with a screw-thread, G, cut upon the valve-stem C, of very much higher pitch than is the screw-thread F. The result 55 is that turning the hand-wheel D in the first place elevates itself by the elevation of the screw-thread F, thereby raising the valve; and, secondly, causes the stem C to be very rapidly moved by the screw-thread G. 60

Attached to the lower end of the stem C is the double wedge-block H and the fixed collar or shoulder O.

Fast to the wedge-block H are four pins, M, 65 two on each side. These pins slide in diagonal or slanting slots N in lugs K, attached to the valves, one lug being situated on either side of the central line of each valve. Furthermore, two loose wedges, J J, are carried in the valve, having pins passing through lugs L in 70 said valve, which pins or rods are adapted to bring up against the base of the valve-chest and to firmly close the valves, as will be explained.

The upper chamber, V, is provided with two 75 slides, R, between which and the sides of said chamber the valves are loosely held when they are raised.

The operation of the valve can now be readily understood. The valve being in the position shown in Fig. 2, suppose the hand-wheel 80 to be turned so as to elevate the stem C, the first result will be that the wedge-block H will leave its contact with the wedges J, which have forcibly seated the valves, the pins M, 85 rising in the slanting slots in the lugs in the valves, will withdraw the valves from their seats, and the block H, coming in contact with the metallic arms or webs W, as shown in Fig. 3, will take up both the valves together and 90 raise them entirely free of the gas-pipe. A continued elevation of the wheel in Fig. 3 will raise the valves A A into the chamber V and leave the pipe entirely unobstructed. On reversing the movement of the wheel the apparatus will once more come into the position 95 shown in Fig. 3. On further depression the valves will be lowered opposite the seats S S S. The continued depression of the valve-stem C will then throw the wedge-block H 100 against the wedges J J, the stems of which have brought up against the bottom of the

valve-chest, thereby, in combination with the pins and slots M N, causing the valves to spread or separate and to be firmly seated against their seats. The valves themselves 5 are held down by the shoulder O engaging with the upper surface of the webs W.

What I claim as my invention, and desire to secure by Letters Patent, is—

The combination of two valves adapted to 10 seat against opposite seats and forced against them by an intermediate wedge-block de-

pressed by a stem and two sliding wedges, one attached to and movable in each valve, which movable wedges engage with the single central wedge when depressed by its stem, for 15 the purpose of closing the double valve, substantially as described.

THOMAS F. ROWLAND.
